UNITED STATES PATENT OFFICE.

JAMES H. PHELPS, OF SHARON, WISCONSIN.

ROTARY ENGINE.

SPECIFICATION forming part of Letters Patent No. 293,511, dated February 12, 1884.

Application filed July 19, 1883. (No model.)

To all whom it may concern:

Be it known that I, JAMES H. PHELPS, a citizen of the United States, residing in Sharon, in the county of Walworth and State of Wisconsin, have invented a new and useful Improvement in Rotary Engines, of which the following is a specification.

My invention consists in a rotary engine of novel construction specially adapted to obtain the greatest amount of benefit and expansive force of the steam.

The nature of the invention will be fully understood from the following description and the drawings, in which similar letters of reference indicate like parts.

In said drawings, Figure 1 is a vertical section of my improved engine, and Fig. 2 is a horizontal section thereof upon line 22 of Fig. 1. Fig. 3 is a detail view, showing the piston-packing.

In the drawings, A. A' represent the case or shell of the engine fitted with heads B.

In the larger part A of the case is the rotating piston C, carrying the abutment C', traversing the steam-space C³. Upon this abutment is an adjustable packing device, c, secured thereto by bolts c', the bolt-opening through said packing being elongated, so that the same may be set out and fit snugly against the interior of the case A. The piston is mounted upon the shaft C³.

In the part A' of the case is the rotating valve D of the same diameter as the solid part of the piston, with which it rotates in steam-tight contact. It rotates upon shaft D', and is provided with a recess, D², which receives the abutment of the piston, and also serves the further purpose of admitting steam as it passes the ports e e' e² e³, (shown in dotted lines in Fig. 1,) and located in the head of the part A'. These inlet-ports I use in such number as is desirable, and the first one is preferably shaped, at the side which is first uncovered, to conform to the valve-recess, substantially as shown, in order that a large amount of steam may be admitted the instant the exposure of the port by the valve begins. In this manner the steam is admitted quickly and in sufficient quantity to begin its labor upon the piston at once. The other side of the ports may be made to correspond with the farther side of the valve-recess,

so that the steam will be shut off at once instead of gradually, as would be the case if the ports did not conform to the valve-recess. The steam passes through these ports only while they are uncovered by the valve-recess, and in order that such as issues through the more remote ones may find its way into the steam-space surrounding the piston, I provide a passage-way, F, extending from the last port over to the piston steam-space, whereby fresh steam is admitted to said space continuously from the time the first port is uncovered until the last one is completely closed.

To prevent passage of the steam in the opposite direction around the valve, a packing, G, is inserted in the case A', and projected against the periphery of the valve by set-screws H. These set-screws I prefer to make with two differentially-threaded portions. Thus the part h may be threaded with a thread of—say, twelve to the inch—and this part will engage with the case A', while the point h', which is of less diameter, may be threaded with a pitch—say, sixteen to the inch—and engage in an opening 75 in the packing G. The result of this feature is that the packing may be adjusted with the nicety required, and jam-nuts H' may be used with the screws H. The steam-outlet is at g, and as near as may be to the point where the 80 abutment completes a revolution or stroke. By thus locating the outlet the maximum of benefit is received from the expansive force of the steam. The piston and valve are of course uniform in their speed of revolution, and are 85 geared together in the usual manner. The abutment is inserted longitudinally and in the body of the cylinder, and the recess in which it is fitted is so shaped as to hold it very rigidly.

In working the engine, steam is admitted by 90 one, two, or more of the ports e e' e², according to the necessity of the work to be done, said ports being controlled in this regard by any suitable valve.

Supposing a sufficient amount of steam can be had through the first port, e, the operation is substantially as follows: Steam will of course issue from said port as soon as it is uncovered by the recess D² in the rotation of the valve, and will continue so to issue until, in the further revolution of the valve said port is closed. The steam thus admitted passes at first directly

and afterward by the passage F into the space C² behind the abutment C'. Inasmuch as the port e remains thus open during a considerable part of the rotation, a goodly quantity of steam is admitted to do duty, and its expansive force is felt by the piston until the out-port g is passed, and the motion thus obtained carries the parts around until the port e is again uncovered. It will be seen from this that if the port e' be also open more steam will be admitted to the piston, and that if three or four ports be used at the same time, the quantity will be still larger, in the latter case the steam being admitted during nearly one-half of the revolution.

It will be noticed that at the time the steam begins to issue into the space D² the piston is in such position that no back-pressure can be exerted upon it, the peripheries of the cylinder and valve rotating in steam-tight contact and sustaining such back-pressure without loss of power.

The inlet-ports e e', &c., are located preferably in both the heads B, but may be employed in only one head.

I claim—

1. The combination, with the piston and its

abutment, of the valve formed with the recess D² and rotating in unison with said piston, and the inlet-ports e e', opened and closed by said valve, substantially as specified.

2. The combination, with the piston and its abutment, of the valve having the recess to receive the abutment and rotating in unison with said cylinder, the inlet-ports opened and closed by said valve, and the passage F, substantially as specified.

3. The rotary engine consisting of the piston and its abutment, and rotating in unison with the piston, the valve having the recess to receive the abutment, the inlet-ports opened and closed by the valve, and the outlet-port located near the end of the stroke, substantially as and for the purpose specified.

4. The combination, in a rotary engine, of the piston and its abutment, the valve and its recess, and inlet-ports opened and closed by said valve, with one or more sides corresponding to the recess in the valve, substantially as and for the purpose specified.

JAMES H. PHELPS.
